UNITED STATES PATENT OFFICE

WILLIAM EMERY NICKERSON, OF BOSTON, MASSACHUSETTS, ASSIGNOR TO GILLETTE SAFETY RAZOR COMPANY, OF BOSTON, MASSACHUSETTS, A CORPORATION OF DELAWARE

BLADE SHARPENING MACHINE

Application filed August 24, 1927. Serial No. 215,238.

This invention relates to blade-sharpening machines, and more particularly to machines for sharpening blades having curved edges. The object of the invention is to provide a machine which will automatically sharpen such blades with accuracy and uniformity, and which will be capable of such adjustments as will adapt it to produce the curvature desired in any given blade edge, the thickness of the blade, and the angle, width and concavity of the edge bevel.

The features in which my invention reside are hereinafter described in connection with the accompanying drawings, in which—

Fig. 1 is a plan view of the machine;
Fig. 2 is a vertical section on the line 2—2 in Fig. 1;

Fig. 3 is a section on the line 3—3 in Fig. 1;
Fig. 4 is a plan view illustrating one adjusted relation of the blade-holding parts to the abrading wheel during the sharpening operation;

Fig. 5 is a similar view showing the blade-holding parts in loading and unloading position.

Fig. 6 is a detail view illustrating the construction of the blade support;

Fig. 7 is a detail view in section on the line 7—7 in Fig. 4;

Fig. 8 is a section on the line 8—8 in Fig. 1;

Fig. 9 is an elevation of the blade-supporting unit as viewed from the front of the machine;

Fig. 10 is a detail view, in section, of a part of the unit shown in Fig. 9;

Fig. 11 is a horizontal section taken on line 11—11 in Fig. 3 and

Fig. 12 is a plan view of a blade on which the machine is adapted to operate.

Figs. 3—12 inclusive are drawn to a larger scale than the remaining figures.

In general, the machine illustrated includes a blade-carrying unit and an abrading unit which are conveniently supported by individual base pieces bolted to a general base plate A, to which also are secured certain other parts employed for producing various movements in the operating cycle, during which there is a relative oscillatory movement in a predetermined path between the

blade and the sharpening means, the former being acted upon during such oscillatory movement by an abrading element included in the sharpening means. Said element preferably consists of a rotating disk of which the angular position of the axis relative to the portion of the edge being sharpened remains constant during the period of contact between said disk and the blade, and provision is made for moving the blade into a convenient loading and unloading position after it has been operated upon by the abrading disk. The parts are so constructed that such adjustments may be made as will enable the machine to produce accurately-formed edges of any desired curvature and bevel contour within the limits of adjustment.

The parts constituting the blade-holding unit in the machine illustrated include a base piece B carrying a fixed vertical spindle B1, having journaled thereon a sleeve B2 which may have a ball-bearing B3 interposed between its lower end and the top of the base piece B, the sleeve B2 being oscillated as hereafter described. A blade clamp is secured to the top of another sleeve B4 rotatable about the same axis as the sleeve B2 and here shown as journaled on the spindle B1 and resting on the upper end of the sleeve B2. The sleeve B4 is independent of sleeve B2 in its movements except as later described, thereby providing for the movement of the blade-clamp into loading and unloading position, but during the sharpening operation these two sleeves are caused to oscillate in unison by means of a coiled spring B5 surrounding the sleeve B2 and secured at its ends to the two sleeves respectively, this spring being under sufficient tension normally to hold a stop B6 on the sleeve B4 firmly against another stop B7 on the sleeve B2 during the oscillations of the latter sleeve. The stop B6 on the sleeve B4 is shown as a solid stop, Figs. 2 and 9, and the stop B7 on the sleeve B2 may consist of a bolt horizontally and adjustably mounted in a bracket B8 secured to the sleeve B2.

The blade clamp, of which the details are shown in Figs. 4, 5, 6 and 7 includes horizontal top and bottom plates B9 and B10 respectively. The plate B10 is preferably made

adjustable circumferentially on the top of the sleeve B4, as by locating the bolts B11 which secure these parts together in circumferential slots B12 formed in the top of the sleeve B4, as shown in Fig. 6. By this adjustment the sector of the blade edges presented to the sharpening device during the oscillation of the sleeves is so determined that the point of the blade travels just to the abrading device on each oscillation.

The upper clamping plate B-9 may be pivoted to a block B-13 bolted to the rear edge of the plate B-10, the hinge pintle B-14 being surrounded by a coiled spring B-15 which swings the plate B-9 upward whenever such movement is permitted. At its front edge the upper clamp plate B-9 has an outline similar to that of the blades to be operated upon, as shown in Fig. 4, and overlies a plate B-16, on which the blades rest during the sharpening operation, the plate B-16 being detachably secured to the front portion of the bottom plate, B10 and being provided with suitable means for positioning the blade such as the pins B-17 shown in Fig. 4. The contour of the upper clamp plate B-9 and the location of the positioning pins B-17 shown in Fig. 4 are suitable for use with the specific form of blade B-18 illustrated in Fig. 12 which is provided with a perforation B-19 and has a straight back edge. The blade is positioned on the plate B-16 by placing its back edge against the outermost pins B-17 and passing an intermediate pin through the perforation B-19 in the blade, Fig. 4, and is rigidly held in this position during the sharpening operation by means of the upper clamp plate B-9 which is forced downward on it as hereinafter described. The plate B-16 can be removed and replaced by another having positioning pins differently spaced and located thereon to adapt the machine to sharpen blades of various sizes and shapes. At its front edge on the under side the clamp plate B-9 is preferably provided with a small leaf spring B-20 located in a recess formed in the clamp plate and serving to hold the blade upon the plate B-16 during the first part of the upward movement of the plate B-9, thereby preventing the blade from adhering to the later plate and being lifted with it.

For forcing the upper clamp plate B9 downward and causing it to grip the blade during the sharpening operation, I employ a plunger C movable vertically in the front end of a bracket C' secured to a standard C2, which is carried by the general base plate A at the rear of the machine. The axis of the plunger C is coincident with the axis of the spindle B1 and when the plunger is forced downward, its smoothly finished lower end bears on the top of a smooth stud B21 secured to the upper clamp plate B9 and projecting upward therefrom, thus enabling the

horizontal oscillatory movements imparted to the blade clamp to take place while the blade is firmly gripped between the clamping plates. The plunger C is operated by means of a lever C3 pivotally supported on the bracket C2 and connected at its front end to the upper end of the plunger C by means of a link C4. Near its rear end the lever C3 is connected to the standard C2 by a coiled spring C5 tending to lift the plunger C, the plunger being forced downward by means of a pull rod C6 connected at its lower end to the rear end of the lever C3 and at its upper end to a suitable operating mechanism which will be hereinafter referred to as the "overhead mechanism". The guide pin C7 projecting from the plunger C into a vertical slot C8 in the bracket C' overcomes any tendency of the plunger to turn on account of the frictional drag exerted on it by the oscillating blade carrier at their point of contact. The "overhead mechanism" is diagrammatically illustrated in Fig. 2, by the cam drum K-20 levers K-22, and pressure controlling valve casing K-28 and may be constructed in accordance with the overhead mechanism shown and described in my prior Patent No. 1,235,590, dated August 7th, 1917, in which Figs. 18, 19 and 20 illustrate the mechanism in question. Briefly described, this mechanism includes a rotary drum carrying a number of cams each of which serves to lift a pull rod (such as the rod C6 in the present machine), and a driving and timing mechanism which controls the operation of the cam drum, according to cycle of operations of the machine with which it is used. In the present case the cams employed will have such shapes and will be so located with reference to one another as to operate the various parts of the machine according to the cycle hereinafter described. It will be observed on reference to Fig. 18 of my prior patent that each of the pull rods has a spring interposed between it and the cam-operated lever which lifts it, and the same arrangement is employed in connection with the present machine, so that after any pull rod such as C6 has completed its upward movement the corresponding spring will provide for a certain amount of lost motion in the operating cam.

The abrading unit, the parts of which are carried by the standard C2, includes a rotary abrading disk D, which may be made of any material suitable for grinding, honing or stropping as desired, mechanism for rotating it continuously, and means for accurately adjusting it in various ways with reference to the blade, the desirable adjustments being such as will determine the radius of curvature of the blade edge and the width and concavity of the bevel. In designing the abrading unit, the point of contact D', Fig. 3, between the blade and the abrading disk D is taken as a reference point and is assumed

to lie at the bottom of the disk, midway between its sides.

The disk D is removably clamped on the end of a spindle D-2 journalled in a suitable bearing D-3, and driven from a countershaft D-4 by flexible driving means, as the belt D-5, the countershaft D-4 being journalled in blocks D-6 located near the rear of the machine and carried by a support 10 D-7, Figs. 3 and 8. Between the bearing D-3 and the support D-7 is interposed an arm D-8 which has the bearing D-3 at its forward end, and is pivotally connected at its rear end to the support D-7 by providing 15 it with threaded pivot pins D-9 having points extending into lugs D-10 carried by the support D-7 in such manner as to enable the disk D to be raised and lowered in its plane sufficiently to move it out of or into 20 contact with the blade B-18.

The abrading action of the disk in a downward direction may be limited by means of a stop screw D-11, Fig. 3, which is preferably made adjustable vertically by thread- 25 ing it into the arm D-8, the screw D-11 resting at its lower end on a bearing plate D-12 mounted on a carriage D-13, which also serves indirectly to carry the support D-7, the vertical position of the carriage 30 D-13 with reference to the base A being fixed. The upper end of the stop screw D-11 is preferably provided with a head D-14 by means of which it may be turned and which may have thereon a graduated 35 scale D-15, Fig. 1, the adjustment of the stop screw D-11 being indicated by the position of this scale with reference to a suitable index such as the upstanding post D-16 fixed in the arm D-8 as shown in Fig. 3. A 40 spring D-17 may also be secured to the arm D-8 and provided at its upper end with a projection D-18 adapted to enter any one of a number of shallow notches D-19 formed on the outer edge of the head D-14, thus 45 serving to hold the screw D-11 against accidental displacement after adjustment. By means of this stop screw the extent of the abrading action may be so limited that in grinding, for example, only the upper half 50 of the blade will be acted upon.

That side of the support D-7 which is remote from the belt D-5 is provided with bearing portions, whereby the support is pivotally mounted on a pintle D-20, carried 55 by two upwardly and laterally directed arms D-21 in turn carried by a block D-22, the pintle D-20 being so positioned that its axis, if prolonged, would pass through or closely adjacent to the above described reference point D1 so that by turning the support D-7 on this pintle, the angular position 60 of the plane of the disk D may be adjusted with respect to the plane of the blade without materially varying the point of contact between the disk and the blade. This

adjustment may be made and maintained by means of a rod D-23, Fig. 8, secured at its upper end to a link D-24 pivoted to the underside of the support D-7 adjacent to the belt D-5, and having its lower end passing loosely through an elongated aperture D-25 formed in an ear D-26 which projects laterally from the rear end of the carriage D-13, the rod D-23 being provided at its lower end with a pair of locking nuts D-27 70 adapted to engage the upper and lower faces respectively of the ear D-26, whereby the rod may be adjusted with respect to the ear D-26 and slot D-25 and locked in any desired position. 80

The block D-22 is provided with a downwardly extending circular boss D-28 which is received in a similarly shaped recess in a slide member D-29 extending downward into a slot D-30 in the bifurcated rear end 25 of the carriage D-13. The block D-22 may be angularly adjusted with respect to the slide member D-29 by loosening the bolts D-31 which pass through circumferential slots D-32 in the block D-22 and are 30 threaded into the slide member D-29. A bolt D-33 passes centrally through an aperture in the slide member D-29 and is threaded into the block D-22, this bolt having a washer or enlargement adapted to engage the 35 carriage D-13 on both sides of the slot D-30 and thus hold the slide member D-29 in adjusted position in the slot D-30. The purpose of the angular adjustment between the parts D-29 and D-22 is not primarily 100 for use in the operation of the machine, but rather to compensate for inaccuracies in the making or assembling of the various parts, so as to bring the reference point D1 exactly 105 over the edge of the blade at their point of contact and in the desired position relative thereto. When the slide member D-29 is adjusted longitudinally of the slot D-30, the bolt D-23 must be similarly adjusted in the slot D-25. 110

The carriage D-13 is provided in its underside with an arc-shaped groove in which is located an arc-shaped bracket D-34 bolted to the standard C2, so that the carriage D-13 and all the parts supported by it can be adjusted on this bracket, the center of curvature of which substantially coincides with the reference point D-1 on the disk D, and therefore, also with the spot being acted upon. The effect of such adjustment 115 of the carriage is to change the angle of the plane of the disk D with respect to a line tangent to the blade edge at the point where the disk D bears on it, and consequently this 120 determines the direction of the abrading action with respect to the blade edge. This adjustment when once made does not need to be altered, and in practice it will suffice to secure the carriage D-13 in a predetermined 125 one of several different angular positions by 130

providing the bracket D-34 with a number of threaded apertures D-35 into any one of which a clamping bolt D-36 passing through the carriage may be screwed.

Provision is made for automatically raising and lowering the disk D by means of a pin D-37 which passes through the carriage D-13 and is capable of sliding vertically therein, its upper end being located directly beneath a boss D-38 formed on the underside of the arm D-8. Beneath the lower end of the pin D-37 is located a pressure-operated cylinder D-39, the upper end of which is enlarged and serves to support the lower end of the pin D-37 in any position of the carriage D-13. The piston D-40 is provided with an enlarged base D-41 rigidly fixed to the base A and has a perforation D-42 passing through it from end to end in line with the open end of a pipe D-43 passing through the base A and adapted to convey fluid under pressure to the interior of the cylinder, the admission of the fluid to the pipe D-43 being automatically controlled in any desired manner, as by the overhead mechanism above referred to, which may include a suitable controlling valve K28 operated by one of the cams on the drum as explained in my prior patent above referred to. The admission of fluid pressure to the pipe D-43 will result in lifting the cylinder D-39 and with it the pin D-37 until the latter strikes the boss D-38, thereafter lifting the arm D-8 and disk D until the upward movement of the cylinder D-39 is arrested by the engagement of its upper end with the underside of the carriage D-13, and when the fluid pressure is relieved, the arm D-8 is moved downward by its own weight.

The blade support may be oscillated to effect the grinding operation by means of a link B-22 having a universal-joint connection at one end to a projection B-23 extending laterally from the sleeve B-2 and at its other end to a crank pin B-24 carried by a disk B-25 which is mounted on a countershaft B-26 located at the rear of the machine and journaled in fixed brackets B-27 secured to the base A, the countershaft B-26 being provided with a driving pulley B-28 by means of which it is continuously rotated from any suitable source of power.

In order to provide for varying the amplitude of the oscillations of the sleeves B-2 and B-4, the crank pin B-24 may be adjustably secured in a radial slot B-29 in the crank disk B-25, in which case a change in the position of the pin B-24 in the slot B-29 will change the eccentricity of the crank and consequently the throw of the link B-22.

The upper part of the blade support may be moved into loading and unloading position by means of a horizontal swinging arm B-30 located behind the blade support and pivoted at one end to a bracket B-31 secured to

the base piece C-2. At its free end the arm B-30 is pivoted to a curved link B-32 having a slot B-33 through which passes a pin B-34 carried by an arm B-35 which is secured to the sleeve B-4, and between its ends the arm B-30 is connected by a link B-36 to one arm of a bell crank lever B-37 pivotally mounted on the base piece C2. The other arm of the bell crank lever B-37 is connected to a pull rod B-38 which extends upward to and is movable upwardly by the overhead operating mechanism previously referred to, against the tension of a coiled spring B-39 which connects one arm of the bell crank lever B-37 and a point on the base piece C-2. While the blade is being operated upon, the spring B-39 maintains the links B-30 and B-32 in the position shown in Fig. 4, the slot B-33 being of such length that the pin B-34 can move back and forth in it while the sleeve B-4 is oscillated by the rotating crank disk and linkage above described, but when the pull rod B-38 is moved upward by the overhead mechanism, the link B-36 is drawn backward whereupon the link B-32 moves freely until the front end of the slot B-33 reaches the pin B-34, the sleeve B-4 then being moved to the position shown in Fig. 5. The blade holder is then in the loading and unloading position, where the blade is out of range of the action of the disk D. The movement takes place against the resistance of the spring B-5, thus enabling the oscillations of the sleeve B-2 to continue irrespective of the position of the sleeve B-4. The loading and unloading position is determined by the adjustment of a suitable stop, such for example as the stop bolt B-40, Figs. 4 and 5, carried by the base piece C-2, the front end of the bolt being engaged by the arm B-30 when it is pulled backward.

Adjustment of the stop bolt B7 has the effect of changing the point on the blade edge at which the abrading action of the disk D begins at the heel of the blade edge, the path of oscillation of the blade carrier being adjustable as to length or amplitude as described above exactly to cover the distance between the heel of the edge and its point.

The pressure of the abrading disk D on the blade may be determined by a weight consisting for example of a number of disks D-44 strung on a rod D-45 suspended on a hook D-46, Fig. 3, which is secured to the underside of the bearing D-3 with the lower end of the rod passing downward through a hole A' in the base A. By adding or subtracting disks the applied weight can be regulated as desired.

The construction and timing of the overhead mechanism is such that after the blade support moves into the loading position shown in Fig. 5, the plunger C is lifted and thereupon the holding plate B-9 is swung

upward by means of the spring B-15. After a blade to be sharpened has been positioned on the plate B-16 the plunger C is forced downward by means of the parts C-4 and C-3 actuated by the overhead mechanism through the pull rod C-6, causing the plate B-9 to clamp the blade on the blade support. The tension on the pull rod B-38 is released and it is drawn downward by the spring B-39, and the blade support moves into the position shown in Fig. 4, the abrading disk at this time being held out of contact with the blade by the fluid under pressure in the cylinder D-39. The fluid pressure in this cylinder is then exhausted, permitting the disk D to move down into contact with the blade, and since this disk rotates continually and the blade support as a whole is oscillated continually, the abrading action begins as soon as the disk touches the blade and continues until the bevel has been sufficiently operated upon. Fluid pressure is then admitted to the cylinder D-39 by the automatic mechanism and lifts the disk D out of contact with the blade, the blade support B-4 then being swung into the loading and unloading position, Fig. 5, by the overhead mechanism operating through the pull rod B-38, the plunger C being lifted, and the top plate B-9 swinging upward. The blade is then removed and replaced by another, whereupon the cycle of operations is repeated.

It remains to describe certain effects of various adjustments provided for in the construction of the sharpening unit. These effects will depend to some extent upon the transverse contour of the periphery of the sharpening disk, which is preferably flat, as shown, and they will be described on the assumption that a disk having this contour is employed.

If the plane of the disk were perpendicular to the plane of the blade and to the direction of its edge at the point of contact, the resulting blade bevel would be concave and would conform in curvature to the disk itself, and on a blade of given thickness the width of the bevel would depend upon the curvature of the disk, assuming the action of the disk to be limited to the upper half of the blade. An increase in the diameter of the disk would result in a bevel of increased width and radius of curvature, and a decrease in the diameter of the disk would result in a bevel of less width and radius of curvature. If the plane of the disk were tilted with respect to the plane of the blade, without otherwise changing their relations, the shape of the bevel would not be affected, but the abrading action of the disk would be confined to one of its corners.

On the other hand, if the plane of the disk were perpendicular to the plane of the blade but parallel with the direction of the blade

edge at the point of contact, the disk would grind a rabbet at the edge of the blade, and in order to make it grind a bevel it would be necessary to tilt the plane of the disk with respect to the plane of the blade. The angle and width of the bevel thus produced would depend upon the angle of tilt, but at any angle the bevel would be flat and not concave, and its width could not exceed the thickness of the disk.

In the illustrated machine the angle between the plane of the disk and the plane of the blade can be varied by adjusting the arm D-8 angularly about the axis of the pintle D-20, and the angle between the disk and the direction of the blade edge at the point of contact can be adjusted by moving the carriage on the arc-shaped bracket D-34, both of these adjustments being limited to a certain range which suffices for all practical purposes, although the range of movement of the carriage on the bracket D-34 is such that the disk never crosses the blade edge at a right angle thereto. In any such intermediate adjustment of the disk tilting is necessary to cause the whole width of the cylindrical surface of the disk to bear on the blade. The position of the abrading disk transversely with respect to the edge of the blade may be varied by adjusting the arm D-8 with the slide member D-29 longitudinally along the slot D-30 in the carriage D-13. It follows from the foregoing explanation that adjustments of the carriage on the bracket D-34 serve to vary both the concavity and the width of the bevel on the blade, while adjustments of the disk about the axis determined by the pintle D-20 serve primarily to distribute the wear over the entire periphery of the disk, the result of each adjustment being affected to some extent by the other. In practice the adjustment of the carriage is limited to a small range about the arc-shaped bracket in which range it is employed chiefly to determine the width of the bevel, the change in the concavity being relatively unimportant. By suitably combining these adjustments a blade bevel of any desired contour, within certain limits, may be readily produced.

It will be observed that the mechanism described is adapted to sharpen one bevel only, and in order to sharpen the other bevel I employ a similar machine with the parts of the blade carrier and the abrading unit reversed in position in an obvious manner, but otherwise exactly similar to the machine described.

While the specific apparatus above described is designed for sharpening blades having curved edges, it will be evident that various features of the invention are applicable to machines for sharpening blades having straight edges, and that the details of construction and arrangement may be wide-

ly modified without departing from my invention.

I claim:

1. In a machine for sharpening curved edge blades, a blade holder, an arm pivoted for movement in a vertical plane, a shaft journaled in the arm, an abrading disk mounted on the shaft, means for driving the shaft in various positions of the arm, automatic means for raising and lowering the arm, means for causing the disk to bear with a predetermined pressure against the blade being sharpened, means for oscillating the blade holder in the plane of the blade so as to bring every point of the edge to be sharpened into contact with the abrading disk, and adjustable means for limiting the movement of the disk towards the blade.
2. In a blade sharpening machine, a circular abrading disk, means for oscillating a curved blade beneath a point in the periphery of the disk, a shaft on which said disk is mounted, an arm adjacent to one end of which said shaft is mounted, a carriage supporting said arm, and an arcuate support having its center of curvature adjacent to the point of contact between the abrading disk and the blade around which center the carriage is movable, whereby to vary the angle between the plane of the abrading disk and the blade edge at their point of contact and consequently to vary the width and degree of concavity of the bevel.
3. In a machine for sharpening curved-edge blades, an abrading disk adapted to be rotated with its plane at an acute angle to the blade edge at its point of contact, a shaft on which said disk is fixed, an arm adjacent to one end of which said shaft is rotatably mounted, a support carrying said arm, a carriage upon which said support is pivotally mounted, the axis of movement of said support being located adjacent to the point of contact between said disk and the blade, means for adjusting the position of said support relatively to said carriage, whereby to vary the angle between the plane of the blade and the plane of the disk, and an arc-shaped support having its center of curvature adjacent to the point of contact between the disk and the blade around which said carriage is adapted to be moved, whereby to vary the angle between the plane of the disk and the edge of the blade at the point of contact and consequently to vary the width and concavity of the blade bevel.

4. In a blade sharpening machine, an abrading tool, a blade holder mounted for oscillatory movement, means for oscillating the holder, a movable blade clamping member carried by said holder, and an operating member located outside said holder and having a point bearing with said clamping mem-

ber located in alignment with the axis of oscillation of the holder.

5. In a blade sharpening machine, a driven abrading disk, a two-part blade holding unit mounted for movement about an axis perpendicular to the plane of a blade held therein, power operated means for oscillating the unit in a predetermined path to effect the grinding operation, and automatic mechanism for extending the movement of one part only of the unit beyond its normal oscillation to carry the blade out of range of the abrading disk.

6. In blade sharpening machine, a rotary abrading disk, an oscillatory blade holder comprising a base part and a blade clamping part movable about the same axis, means connected to the base part for oscillating the holder as a unit, and separate mechanism connected to the blade clamping part for oscillating that part independently of the base part.

7. In a blade sharpening machine, a rotary abrading disk, an oscillatory blade holder for a curved edge blade, means for oscillating said holder in a predetermined path, and operating means having a lost motion connection with said holder while it moves in its normal path arranged to impart an additional further movement to the holder at predetermined intervals.

8. In a blade sharpening machine, a rotatable blade holder including a pivotally mounted sleeve and adjustable clamping means disposed at one end thereof, an abrading disk movably disposed in operative position adjacent said clamp, means for moving one edge of said clamping means beyond the range of the abrading disk and cooperating means for moving said disk away from said blade holder to permit adjustment of said clamp.

9. In a blade sharpening machine, a power operated holder for securing articles to be ground and movable therewith in a curved path, a vertically movable arm arranged above said article, an adjustable stop for positioning the arm in a predetermined vertical position, a rotatable abrading disk at the free end of the arm and a fluid actuated device for raising said arm from said stop.

10. In a machine for sharpening curved blades the combination with a rotary abrading disk, of a blade holder, mechanically actuated means for oscillating the holder to present every point in the edge of a curved blade to the action of the disk, and automatic means for periodically extending the movement of the holder beyond the normal range of its oscillating movement to locate it in loading or unloading position.

11. In a machine for sharpening curved edge blades, a rotary abrading disk, a two-part oscillatory blade holder cooperating therewith, power operated mechanism for

oscillating the holder as a unit about its axis to grind a blade in the holder while leaving one part of the holder free for independent oscillation about the same axis, and means for 5 independently oscillating said part to carry the sharpened blade beyond the range of the abrading disk.

12. In a blade sharpening machine, a driven abrading disk, means for oscillating a 10 curved blade beneath the disk, a shaft carrying the disk, a pivotally mounted arm in the free end of which said shaft is mounted, a carriage supporting the arm and being bodily adjustable in an arcuate path having as its 15 center of curvature the point of contact of the disk with the blade, and provision for bodily adjusting said arm and disk transversely with respect to the edge of the blade being sharpened.

20 Signed at Boston, Massachusetts, this twenty-third day of August, 1927.

WILLIAM EMERY NICKERSON.
